(57) **CLAIM**

The ornamental design for an emergency power supply, as shown.

DESCRIPTION

FIG. 1 is a front elevational view of an emergency power supply showing our new design;
FIG. 2 is a rear elevational view thereof;
FIG. 3 is a left side view thereof;
FIG. 4 is a right side view thereof;
FIG. 5 is a top plan view thereof;
FIG. 6 is a bottom plan view thereof;
FIG. 7 is a perspective view thereof; and,
FIG. 8 is another perspective view thereof.
